UNITED STATES PATENT OFFICE.

EDWARD T. WILLIAMS, OF NEW YORK, N. Y.

MAGNETIC CLUTCH.

Application filed October 15, 1923. Serial No. 668,508.

To all whom it may concern:

Be it known that I, EDWARD T. WILLIAMS, a citizen of the United States of America, residing at New York, county of Kings, and State of New York, have invented certain new and useful Improvements in Magnetic Clutches, of which the following is a full, clear, and exact description.

In machines for handling gases, as for example pumps, compressors, blowers, exhausters, and the like, in which a driving or other rotating shaft extends out of the machine for connection with an external shaft, considerable difficulty is experienced in preventing leakage out of or into the machine or casing, along or around the shaft. One method which has been proposed for meeting the conditions mentioned is to couple the two shafts magnetically, and cover the outer end of the inner shaft hermetically by means of a cup of non-magnetic metal which will permit the magnetic flux of the driving element, rotating around the cup, to pass to the driven element housed in the cup. My present invention relates to this method of connection, and its chief object is to provide a coupling in which the energizing coil or winding, by which the magnetic flux is produced, may be stationary, thereby dispensing with slip rings or other moving contacts for carrying the energizing current to and from the winding. To this and other ends the invention consists in the novel features and combinations of elements hereinafter described.

One form of the invention is illustrated in the accompanying drawing, in which—

Fig. 1 is a longitudinal section through the axis of the coupling.

Fig. 2 is a cross section on line 2—2 of Fig. 1.

In the drawing, 10 represents the wall of a compressor or other machine, having a neck 11, constituting a bearing for a shaft 12 and provided with a radial flange or wall 13 which is removably fastened to the end of, and forms the cover of, a shell or cage 14 which is itself coaxial with the armature shaft 15 of the driving motor 16. The shell or cage is fastened to and carries the motor casing. In the preferred construction the compressor is also carried or supported by the shell 14, through the agency of the neck 11.

The outer end of the neck 11 is extended

in the form of a cup 17 to receive the hub 18, of the driven coupling member 19, by which said coupling member is firmly connected to the shaft, as shown. This coupling member is preferably recessed in its outer face, as indicated, to save weight. The shell 20, composed of thin non-magnetic sheet metal, encloses the coupling member and is hermetically sealed to the neck 11 by means of a flange 21 and clamping ring 22 of dielectric material, as for example the material commonly known as bakelite, the flange 21 being secured to the cup or shell 17 and providing around the latter, in conjunction with the flange 13, a deep annular recess in which is seated the energizing winding or coil 23. This coil is stationary, and is connected to the source of current (not shown) by means of suitable binding posts or terminals, of which one is shown at 24. The annular driving coupling member 25 surrounds the driven member 19 outside of the sealing shell 20 and is carried on the armature shaft 15 by means of a spider 26. Both coupling members are provided with the same number of radial teeth, those on the outer member projecting inwardly and those on the inner member projecting outwardly, as shown. Both sets of teeth run close to the sealing shell 20, preferably with minimum clearance, and the outer surface of the outer member runs close to the rib 27 on the inside of the shell or cage 14. It will of course be understood that the two coupling members, the hub 18, flange 13 and shell 14 are made of iron or steel.

The magnetic circuit, when current is flowing through the coil 23, is indicated by the arrows. Inasmuch as the iron of the teeth on the two coupling members is more permeable to the lines of force than is the air in the recesses between the teeth the magnetic flux will be confined practically to the teeth, with very little leakage. If the motor is running, thereby revolving the coupling member, the latter can revolve around the inner member only by distorting the lines of force passing through the sealing shell 20, but since such distortion is strongly resisted the net result is that the inner member is magnetically locked, as it were, to the outer member, and hence rotates therewith.

I prefer to use direct current for magnetizing the coupling members, but it will

be understood that by suitable modification, well understood by electrical engineers, alternating current may be employed.

It is to be understood that the invention is not limited to the construction herein specifically illustrated and described but can be embodied in other forms without departure from its spirit as defined by the appended claims.

10 I claim:

1. The combination with a machine of the class described, having a casing and a shaft extending through the same, said casing having a tubular extension coaxial with 15 and surrounding the outer end of the shaft; of an inner magnetic coupling member having a hub extending into said tubular extension and secured to the end of the shaft therein, a sealing cup enclosing the 20 coupling member and sealed around the outer end of said tubular extension, an outer magnetic coupling member rotatable around the inner member outside of the sealing cup, and a stationary magnetizing coil surrounding 25 said tubular extension between the casing and the sealing cup and having a magnetic circuit including the tubular extension, hub, and both coupling members.

2. The combination with a shell, an end 30 wall therefor having an inner tubular extension, a shaft extending into the shell and into the tubular extension thereof, an inner magnetic coupling inside of the shell and having a hub extending into the tubular 35 extension and secured to the shaft therein, a sealing cup enclosing the coupling member and hermetically sealed to the tubular

extension, an outer rotatable coupling member rotatable surrounding the inner coupling member outside of the sealing cup, and a 40 stationary magnetizing winding surrounding the tubular extension between the said end wall and sealing cup and having a magnetic circuit through the end wall, shell, both coupling members, and the hub. 45

3. The combination with a driving motor having a driving shaft, of a shell coaxial with said shaft and having one end attached to the motor for support thereby, an outer annular magnetic coupling member carried 50 by said shaft for rotation thereby and having its outer surface close to the inner surface of the shell, an end wall mounted on the other end of the shell and carried thereby, said wall having an opening coaxial with said shaft and a coaxial tubular member extending inwardly around said opening, a driven shaft extending through said opening into the tubular member, a sealing cup hermetically sealed to the tubular member and extending into the annular coupling member, a magnetic coupling member enclosed in said sealing cup and having a hub extending into the tubular member and secured to the driven shaft therein, and a stationary magnetizing winding surrounding 60 the tubular member inside of the shell between the end wall thereof and the sealing cup, and having a magnetic circuit through said hub, end wall, shell, and both coupling 65 members.

In testimony whereof I hereto affix my signature.

EDWARD T. WILLIAMS.
